(57) **CLAIM**

The ornamental design for a display panel with multi-surface mount, as shown and described.

DESCRIPTION

FIG. 1 is a top perspective view of a display panel with multi-surface mount;

FIG. 2 is a front elevation view thereof;

FIG. 3 is a rear elevation view thereof;

FIG. 4 is a right elevation view thereof;

FIG. 5 is a left elevation view thereof;

(Continued)

FIG. 6 is a top plan view thereof; and,
 FIG. 7 is a bottom plan view thereof.
 The broken line portion of the figure drawings is included to
 show unclaimed subject matter only and forms no part of the
 claimed design.

1 Claim, 7 Drawing Sheets
